UNITED STATES PATENT OFFICE.

HERBERT R. NEVENS, OF DORCHESTER, MASSACHUSETTS, ASSIGNEE TO NEVENS-WALLACE TRAIN CONTROL COMPANY, A CORPORATION OF MASSACHUSETTS.

TRAIN-STOP DEVICE.

1,823,091.

Specification of Letters Patent. Patented Nov. 25, 1919.

Application filed March 28, 1916. Serial No. 87,824.

To all whom it may concern:

Be it known that I, HERBERT R. NEVENS, a citizen of the United States, residing at Dorchester, county of Suffolk, Commonwealth of Massachusetts, have invented certain new and useful Improvements in Train-Stop Devices, of which the following is a specification.

This invention relates to automatic train stop mechanism and particularly to that mechanism of a related train stop system which I shall hereinafter term the track installation. As illustrative of a track installation of the general character involved herein, reference is made to the structure disclosed in the application of Lewis R. Wallace, Serial No. 31,932. While having many objects in common with said application, the present invention has certain objects and involves certain fundamental differences not present in said application; as will be explained more fully hereinafter.

The track stop of my present invention is supported for rotation through a quarter of a revolution in a horizontal plane, so as to swing into and out of the path of a brake relief member on the train, and is normally disposed in supported safety position. The support for the track stops is controlled through suitable connections, including a normally closed locking circuit by the condition of the block next ahead. Should the block next ahead be occupied, this locking circuit is broken and the support for the track stop released. This support descends by gravity and by its descent revolves the track stop through a quarter of a revolution to its interfering position or "danger" position in the path of the train-carried brake relief member. The track stop remains in danger position until the conditions which caused it to assume this position are removed, as for example, by the passage of the train which occupies the block next ahead out of said block, or in the case of failure or breakage of any of the parts of the mechanism, by the repair or restoration of such failing parts. In the normal operation of the track stop, the movement thereof to interfering or "danger" position puts a restoring motor, which is included in a normally open restoring circuit controlled by the dominant locking circuit to the block

next ahead, in condition to become effective by the closing of said restoring circuit. The 55 restoring circuit is closed by the closing of the dominating locking circuit and this occurs as soon as conditions are again safe for the passage of the train. This starts the resetting motor, which through operative 60 connections including a rotatable restoring member of special design, lifts the support for the track stop. During this lifting action this support itself is caused to revolve whereby to rotate the track stop to safety 65 position, and be locked in such position, whereupon the motor circuit is broken and the motor stopped.

This restoring member consists of a gear 70 wheel rotated in one direction by the power-transmitting train from the motor to restore the track stop and in the reverse direction by the gravity tendency of the parts to move to unsupported position upon release of the locking mechanism therefor. The gear wheel 75 has lifting engagement with a part on the supporting shaft of the track stop in the restoring movement thereof through a suitable lifter device. This device is mounted for sliding travel across the face of the gear 80 wheel itself, so as to positively eliminate any tendency of the gear to stop at a dead center when the motor is cut out. Should the gear in its restoring movement revolve pass the limit of effective supporting engagement of the slide with the device on the track stop shaft, the slide simply passes 85 from under said device and drops to the opposite end of its slideway by gravity, the shaft drops back to non-restored position, 90 and the slide reengages the lift device thereon as soon as the gear completes its phase of ineffective non-restoring movement and again begins to lift, the arrangement being such that the motor which revolves said gear 95 is not stopped until the track stop is positively restored to safety position.

My present invention, while especially designed to be used as an auxiliary safety device for the block signal system with which 100 most railroads are equipped, may be used as a block signal itself in addition to its train stopping functions. Moreover, the construction is capable of modification to permit the track stop to be disposed in position to co- 105 operate with a train carried trip which is

mounted near the roof of the engine cab, should it be desired to operate from this point.

The construction and operation of my device is fully disclosed in the specification which follows. The drawings accompanying that specification illustrate a practical embodiment of the principles of my invention. Throughout specification and drawings like reference numerals are correspondingly employed, and in these drawings:

15 Figure 1 is an elevation, as viewed from a position along the track, of a train stop in accordance with my invention, the housing for supporting shaft thereof being shown in vertical section to illustrate the supporting mechanism contained therein and the track stop being shown in its danger position.

20 Fig. 2 is a partial view similar to Fig. 1, but showing the parts in vertical section.

Fig. 3 is a transverse section on the line 3—3 of Fig. 2.

25 Fig. 4 is a partial view of a portion of the fixed supporting structure for the track stop.

Fig. 5 is a face view of the rotatable lifting member, removed, which member is operated by the motor to restore the track stop to safety position.

30 Fig. 6 is a plan section through the track box, approximately on the line 6—6 of Fig. 1.

Fig. 7 is a longitudinal section on the line 7—7 of Fig. 6, showing the safety position 35 of the track stop in full lines and the danger or interfering position thereof in dotted line projection.

40 Fig. 8 is a detail view of the control for the motor circuit, removed, and illustrating in full and dotted lines its open and closed position, respectively.

45 Fig. 9 is a view showing a modification wherein the track stop is disposed in a position to actuate a train-carried brake relief device mounted on the roof of the engine cab. Fig. 10 is a view similar to Fig. 1 but showing the position of the parts when the track stop is at safety position. Fig. 11 is a detail section illustrating particularly the 50 planetary gears forming a part of the restoring mechanism, and Fig. 12 is a side section of Fig. 11, partially broken away, and viewed from the right of said figure.

55 The motor and the power transmitting connections therefrom to the supporting structure restoring portion of the track stop as well as the locking mechanism for said supporting structure is contained in a watertight box or casing 10. The track box 10 is 60 located at or near the entrance of a track section or block under automatic signal control, if the railroad is equipped with a block signal system, and is suitably secured adjacent a rail in any desired manner. The top 65 wall of the box 10 is open for a portion of

its area, as indicated at 11, Fig. 7, to permit access to the contained mechanism. This face of the box is closed by a removable cover 12 which may be secured to the top wall by any suitable means, here shown as 70 cam levers 13 and eye bolts 14, which may be positively locked to each other as by the padlocks 15.

The bottom wall of the track box 10 between its ends is formed as a pit or well 16 75 in which is mounted a portion of the supporting structure for the track stop. The supporting structure for the track stop projects vertically through the top of the track box so as to position said track stop at some 80 little distance above the rail and normally substantially parallel thereto. The safety position of the track stop is that indicated in full lines, Fig. 7, in which position the stop is disposed out of the path of a trip arm 85 mounted on the train and controlling the air brake system, preferably independently of the engineer's control valve.

The supporting structure for the track stop consists in part, of a vertically disposed shaft or standard 17 which is rotatably and slidably mounted in a flanged bearing sleeve 18 extending into the track box through an opening in the top wall thereof and having its flange 19 fitted in a 90 counter-sunk opening in the cover 12 so as to be flush therewith, and said flange being preferably screwed to said top wall. That portion of the sleeve 18 which is disposed within the box 10 is provided with an external cam groove 18¹ in which a roll 17¹ fast on the shaft 17 is adapted to work, said roll and groove constituting means for rotating the shaft 17 as said shaft is raised to restore the track stop. Sleeved about the exposed portion of the member 18 is a housing 20.

Near its upper end the sleeve 18 is formed with an internal lug 21 through which the upper end of the shaft 17 extends and has 110 bearing. The upper end of the sleeve 18 is formed as a stationary cam surface 22. The upper end of the shaft 17 is reduced as indicated at 23 to receive the lower bifurcated end 24 of a rod 25 to which is pinned to 115 move therewith a surmounting cap member 26 which carries the track stop, said cap member having an oppositely faced movable cam surface 27 disposed to cooperate with the cam 22 of the sleeve 18.

120 The connection 23—24 of the members 17—25 with the oppositely faced cams 22—27 permits said members relative separating movement, so that the track stop may yield to the impact of the train-carried trip 125 arm while yet delivering to said arm a sufficient actuation to move the brake relief mechanism associated therewith. The yielding connection also safeguards against a train automatically stopping itself should 130

the track stop be left in danger position and be actuated by a train proceeding against the current of traffic, as in the backing. In the normal operation of the installation, the 5 connection 23—24 transmits rotative movement of the shaft 17 to the rod 25 and vice versa, to permit the track stop to move into and out of the path of the train carried 10 brake relief member.

10 The cap 26 has an opening 28 transversely therethrough in which is mounted the longer arm 29 of a bent track stop member. The arm 29 projects laterally from the cap and is bent under itself providing a short arm 15 30 which is carried back toward the standard and passed through a hole 31 in a depending skirt or petticoat 32 sleeved about the cap 26 near its base and inclosing the upper end of the housing 21 and cams 20 22—27. The purpose of this petticoat is to prevent the accumulation of ice, snow or other matter which might tend to interfere with the free swinging movement of the track stop. The upper end of the petticoat 25 32 has oppositely disposed holes therein adapted to be registered with the opening 28 in the cap to receive the longer arm 29 of the track stop. This arm therefore retains the petticoat in position upon the cap, and 30 is itself retained in position against turning movement independent of the rod 25 and the cap 26 by a screw 33 threaded into the cap 26 from the top thereof and disposed to enter a notch 34 cut in the upper face of 35 the arm 29. The open construction of the stop arm presents less resistance to the wind, and reduces the possibility of the arm being swung thereby.

In addition to its retaining function the 40 screw 33 may serve as a supporting journal for a signal lantern (not shown), especially where the installation is to be used both as a block signal system and an automatic train stop mechanism. For this purpose the head 45 of the screw may conveniently be squared, as indicated at 35.

The lower end of the shaft 17 is adapted to be normally supported in raised position through intermediate power-transmitting 50 connections, by an electro-magnetic locking mechanism. This end is also cushioned against the shock met in the descent of the shaft when the support is released. For this purpose the lower end of the shaft 17 55 is axially bored and internally threaded to receive the reduced threaded portion 36 of a piston stem 37, this threaded connection providing a slight vertical adjustment at this point, which adjustment is held by a 60 cotter pin 38. The stem may also conveniently carry an engageable device for the lifting mechanism, and as here shown this device consists of a disk 40 having a depending hub portion 41 sleeved about the stem 37 65 and held thereon by a lock nut 42 which en-

gages a short series of threads 43 on said stem and being further held by a cotter pin 44. The lower end of the stem 37 is reduced and threaded into a piston 45 which works loosely in a cylinder 46 mounted in the pit 70 16 of the track box.

The piston has a slight clearance in the cylinder in order to work relatively freely therein while at the same time offering sufficient resistance to the descent of the shaft 75 17 to prevent undue shock to the parts. For this purpose the cylinder is provided at a proper point with one or more vent ports 47. The shock of the descending parts may be further reduced by suitably cushioning 80 the contacting elements. As here shown a buffer element 48 is mounted on the reduced end of the piston stem 37 at the under face of the piston, and a buffer 49 is supported on a suitable cushioning element 50 resting 85 on the bottom wall of the cylinder.

In the normal safety position of the mechanism the parts are in the position shown in full lines, Fig. 7. In this position the track stop 29 is disposed substantially parallel to the track, and the opposed faces of the cams 22—27 are separated. This position is reached by raising the shaft 17, which movement through the roll 17¹ and cam groove 18¹ causes the shaft to rotate, this rotation causing the cam 27 and stop arm to turn on the cam 22. The means for raising the shaft 17 and for supporting it, consist in part, of a rotatable gear wheel 51 and a sliding lifter 52 carried thereby and disposed to engage under the disk 40 and raise said shaft as the gear is rotated. The shaft 53 of the gear 51 is journaled in any suitable manner in a bearing 54 rising from the floor of the track box. The lifter 52 105 consists of one or more rolls revolvably mounted on a stem 55 which is threaded into a slide 56 having guided travel in the slot of a slide way-forming member 57 fastened to the adjacent face of the gear 51 and extending diametrically therewith at right angles to the axis of rotation of the gear. As the gear is rotated, from the motor, in the restoring action of the device, the slide revolves therewith, engaging 110 and raising the disk 40 and thus the standard 17. In the normal operation when the gear has revolved through substantially a quarter of a revolution, the track stop is fully restored to safety position and the 115 motor is stopped, so that the shaft 17 is supported in raised position (see Fig. 10) by the engagement of the rolls 55 under the disk 40, which engagement is subject to the electro-magnetic locking mechanism applied thereto through the gear 51. Should for any reason the gear 51 continue to revolve sufficiently far to carry the rolls 55 from under the disk 40, or should the position of the gear be at or near a dead center, the slide 120

56 drops to the other end of the slide, the shaft 17 again drops, and as soon as the gear 51 completes its phase of ineffective motion and again begins its lifting phase, 5 the disk 40 is reengaged by the rolls 55 and the shaft 17 again lifted. The arrangement is such that unless the track stop is 10 fully restored and positively supported by the locking mechanism through the gear 51 and the rolls 55, the motor will not be stopped, but will continue to revolve said gear until the parts are positively supported. In the release of the mechanism and a consequent movement of the track stop to danger 15 position, the gear 51 is rotated in the reverse direction of restoring rotation. It will be seen that a dead center is absolutely eliminated, and the possibility of the gear stopping in a position from which it would not 20 be possible to fully restore the stop arm avoided.

The supporting mechanism for the shaft 17 in addition to the gear 51 further consists of a series of intermediate connections, 25 illustrated in detail and claimed in the Wallace application hereinbefore referred to, from said gear to electro-magnetically controlled locking arm. These intermediate connections consist in general of a pinion 30 58 set free on a clutch shaft 59 journaled in a suitable bearing 60 projecting laterally from a casting 61 resting on the floor of the track box. The pinion is formed with an integral clutch part 62 which co-operates 35 with a complementary clutch part 63 mounted on the squared end of the clutch shaft, as in the Wallace application. Between the clutch part 63 and a face plate 64 on the shaft 59 a coiled spring 65 is confined.

40 On the opposite end of the shaft 59 is a pinion 66 which meshes with a gear 67 loose on a counter-shaft 68. The gear 67 carries a series of three pinions 67¹ which mesh with a central pinion 67² fast on the 45 counter-shaft behind said gear. This series of pinions engages the gear teeth on the rim of an internal gear 68¹ loose on the inner end of the counter-shaft, this internal gear providing a housing for the series of 50 pinions and the central pinion, as in the Wallace case.

The rim of the internal gear has a laterally projecting lug 69 which is normally supported by the free end of an electro-magnetically controlled supporting arm 70. The arm 70 is pivoted between its ends on a transverse pivot pin 71 mounted in a suitable casting rising from the floor of the track box and at its opposite end is connected to the upper end of a vertically disposed lever 72. (See Fig. 6.) The opposite end of the lever 72 is linked to a second lever 73 which is pivoted at its lower end in suitable brackets rising from the base of 65 the casting and at its upper end has pinned

to it a longitudinally movable locking arm 74. The arm 74 guides in the supporting casting and has a locking notch with which engages the free end of a pivoted locking dog carried by an armature 75 pivotally mounted on the pivot 71 for the arm 70. The armature 75 is normally held against the cores of a pair of electro-magnets 76, 70 suitably supported within the track box and included in a normally closed locking circuit. 75

The locking circuit to the electro-magnets consists of a lead wire 77 from the binding post of one magnet to the pole of a track battery B and a lead wire 78 from the 80 opposite pole of said battery to the binding post of the other magnet. The locking circuit 77-78 is included in the dominant circuit for the block signals in any desired manner, as by the relay R. 85

When the locking circuit is closed and the magnets energized, the tendency of the armature is to maintain the dog carried thereby in rigid erect locking relation to the notch of the arm 74. When thus held, the dog supports the track stop through the arrangement of intermediate gearing 58-66-67-68 and the series of planetary pinions. When the magnets are deenergized by a break in the locking circuit, the armature is released, and the dog is free to tilt downwardly, destroying the locking relation. 95

The gravity tendency of the released parts causes the gear 51 to rotate the pinion 58 free on the clutch shaft 59. The teeth of the clutch part 62 however, engage the teeth of the part 63 which is fast on the squared end of the clutch shaft, thereby rotating said clutch shaft in a counter-clockwise direction, as viewed in Fig. 7. The pinion 66 on said shaft rotates the gear 67 loose on the counter-shaft clockwise as viewed in said Fig. 7 to move the lug 69 through substantially a quarter of a revolution. In this position of the parts the stop arm 29 has been 100 rotated, by the rotation of the shaft 17 in its descent, through a quarter of a revolution so as to occupy a position of interference in the path of the train-carried brake relief member. When the arm 29 is struck the shafts 17 and 25 through the connection 105 23-24 have a relative separating movement which permits the stop arm to yield to the impact while at the same time delivering an actuation to the train-carried trip sufficient 110 to move the brake relief mechanism connected therewith. 115

The shaft 17 in its descent actuates a circuit controlling device 80 to move said device into a relation which will place a normally open resetting circuit which is included in the locking circuit in condition to become effective when the locking circuit is again closed. This circuit control consists of a radially disposed arm 79 fastened 120 125 130

at one end to a rotatable disk 80 carried by a bracket 81 secured to a wall of the track box, and having its other end formed as a re-fork 82 between the arms of which the reciprocal disk 40 is disposed so as to actuate said arm 79 in either direction of reciprocation. When therefore the disk 40 drops the lower arm of the fork 82 is actuated thereby rotating the disk 80 downwardly 10 through a part of a revolution and carrying an insulated peripheral section 83 thereof out of contact with the contact finger 84 of a binding post 85 so that the member 80 bridges the gap between the contact 84 and the contact finger 86 of an oppositely disposed binding post 87. The binding posts 85 and 87 are included in the normally open resetting circuit from the locking circuit 77-78.

20 This shunt circuit consists of a lead wire 89 from one leg 77 of the locking circuit to the binding post 85. The circuit from this post to the opposite post 87 is across the disk 80 and along the lead wire 88 to one 25 binding post 90 of a restoring motor M, thence across the motor to the opposite binding post 91 thereof and along a lead wire 92 back to the other leg 78 of the locking circuit.

30 When the disk 80 is in its normal position shown in full lines in Fig. 8, the circuit across the binding posts 85-87 is incomplete, due to the contact of the insulation 83 with the member 84. When the stop arm 35 rotates to danger position, the disk 80 is rotated to carry the insulation 83 into the dotted line position shown in Fig. 8, thereby putting the circuit in condition to be closed across the binding posts 85 and 87. Inasmuch as the track stop does not rotate to danger position, however, unless there is a break in the locking circuit and a consequent de-energization of the electro-magnets, the shunt circuit is not closed and is not put 40 in condition to start the motor until the current comes on again in the dominant locking circuit. The parts are simply left in condition to be restored as soon as it is again safe for the passage of the train. In order to 45 hold the disk 80 in one or the other of its two effective positions, I provide a flat spring 93 which is fastened at one end to a wall of the track box and is suitably insulated therefrom and has a detent 94 near its other end 50 adapted to engage one or the other of a pair of adjacent locking notches 95 in the periphery of the disk 80.

When conditions are again safe for the 55 passage of the train, the locking circuit is automatically closed to put the locking mechanism in condition to support the lug 69 when said lug is rotated through the remainder of the revolution initially given it and again assumes a position wherein it 60 may be supported by the arm 70. The resto-

ration of the locking circuit sends current into the shunt circuit to the motor, which now starts and through suitable gearing restores the stop arm 29 to its normal safety position.

This gearing consists of a worm 96 on a motor shaft meshing with a gear 97 on a cross-shaft 98 journaled in suitable bearings rising from the casting 61 and having a gear 99 on its opposite end meshing with a gear 100 on the outer end of the counter-shaft 68. These connections rotate the counter-shaft 68 in a clockwise direction, as viewed in Fig. 7, and the central pinion 67² fast on said shaft and the series of three 80 planetary pinions 67¹ carried by the internal gear 68¹ as well as said gear itself, are therefore rotated with a planetary movement about the shaft 68 as an axis. This carries the lug 69 on said gear through 85 the remainder of the revolution initially given it by the parts in their descent and moves this lug into position to be supported by the arm 70, which arm has previously been placed in a condition to support said 90 lug by the restoration of the locking circuit. The contact of the lug 69 with the arm 70 causes the planetary gears to rotate about their respective axes clockwise as viewed in Fig. 7, thereby rotating the 95 gear 67 counter-clockwise as viewed in said figure, and this gear, through the pinion 66, rotates the clutch shaft 59 in a clockwise direction, causing the clutch part 63 which is fast on the squared end of said shaft to engage the part 62 and rotate it, and thus the pinion 58 clockwise, thereby rotating the gear 51 clockwise, whereby to raise the shaft 17 through the disk 40 and lifter 55. When the gear 51 has rotated through 100 a sufficient portion of a revolution to fully restore the track stop to safety position, the upper face of the disk 80 engages the upper fork of the forked arm 79, rotating the disk 80 counter-clockwise to carry the 105 insulated portion 83 back into contact with the free end of the finger 84, thus breaking the shunt circuit across the disk 80 and cutting out the motor. Should the mechanism fail to fully restore the track stop, the motor 110 is not cut-out but continues to rotate the gear 51 until the arm is positively restored and supported by the rolls 55, as hereinbefore explained. In such action, the clutch elements 62-63 slip past each other so that 115 the position of the internal gear 69 is unchanged.

In the modification shown in Fig. 9, the shaft 17 and associated parts are made of a length sufficient to support the track stop at a considerable height above the rail and in a position to co-operate with a brake relief member mounted on the roof of the cab. This adaptation is especially useful where 120 it is intended that the stud 35 shall carry 125

- 6 a signal lantern, in order that the installation may be used both as an automatic train stop and a block signal. This lantern may be of the usual type, having a bracket or 5 the like which is provided with a squared socket into which ordinarily fits the usual stud on the bracket or arm of the train, but which as here contemplated may be fitted over the stud 35.
- 10 Various modifications in the form and construction of my invention may obviously be resorted to if within the limits of the appended claims.
- What I therefore claim and desire to secure by Letters Patent is:
1. In a train stop mechanism, a movable track stop having an ineffective and an effective position, a supportable element associated therewith, and a releasable support 20 having an engaging relation to said element in the ineffective position of the stop and automatically released by the movement of said stop to its effective position, and means for causing said support to renew its supporting 25 relation to restore said stop to its ineffective position.
2. A track obstacle, comprising a relatively stationary supporting member having a cam surface, a cap surmounting said 30 member and having a cam surface adapted to coöperate with said cam surface thereof, a stop arm mounted on said cap, and a shaft rotatable relative to said supporting member and connected to said stop arm.
3. A track obstacle, comprising a relatively stationary sleeve having a cam surface, a cap surmounting said sleeve and having a cam surface adapted to coöperate with 35 said cam surface thereof, a shaft rotatable within said sleeve, a rod alined with said shaft, a connection between said rod and shaft allowing relative separating movement thereof, and a stop arm mounted on said cap and connected to said rod.
4. A track obstacle, comprising a relatively fixed and a relatively rotatable member having coöperative cam surfaces, a stop arm mounted on said relatively rotatable member, and a sleeve depending from said 45 relatively rotatable member and adapted to protect said cam surfaces.
5. In combination, a rotatable track stop having an effective and an ineffective position, a shaft operatively connected with said 55 stop, and adapted to be operated thereby, a sleeve about said shaft having a connection therewith permitting the shaft both rotative and sliding movement, a gear wheel, a slide carried by said gear wheel and normally 60 engaging said shaft to maintain the same in its raised position, a release for said gear wheel, permitting said shaft to turn and drop, and the track stop to move to effective position, a motor, and power transmitting 65 connections from said motor to said gear

wheel effective to rotate said gear wheel and cause the slide to engage and raise the shaft, to its normal position, rotating said shaft in such raising to move the track stop to ineffective position.

6. In combination, a supportable element having a supported and a non-supported position, a track stop having an ineffective and an effective position according to the position of said element, a rotatable support, a slide carried thereby and movable transversely thereacross and having a supporting and a non-supporting relation to said element, according to the direction of rotation of said rotatable support, and means for 75 positively rotating said support in one direction.

7. In combination, a supportable gravity element having a supported and a non-supported position, a track stop having an ineffective and an effective position according to the position of said element, a gear wheel having a slideway, a slide in said slideway, and having a supporting and a non-supporting relation to said element, and means for 80 positively rotating said gear wheel in one direction, the gravity tendency of the supportable element when released rotating said gear wheel in the opposite direction.

8. In combination, a normally supported 85 member, a track stop associated therewith, a rotatable support for said member having sliding movement transversely of the axis of rotation, and means for rotating said support in one direction.

9. In combination, a normally supported member, a track stop associated therewith, a rotatable support for said member having sliding movement transversely of the axis of rotation, means for rotating said support 105 in one direction, a circuit to said means, and a circuit closer controlling said circuit and disposed for actuation by said normally supported member.

10. In combination, a holder having an 110 opening therein, and a member bent back upon itself and having one portion lodged in said opening and constituting an open sided track obstacle designed to offer minimum resistance to the wind.

11. In combination, a holder having an opening therein, and a member bent back upon itself to provide spaced substantially parallel arms and constituting an open sided track obstacle designed to offer minimum resistance to the wind, one of said arms lodged in said opening of the holder.

12. In combination, a holder having an opening therein, a petticoat having an opening therein, and a member bent upon itself 125 to provide spaced arms designed to offer minimum resistance to the wind, said arms lodged in the openings of the holder and petticoat, respectively.

13. In combination, a holder having an 130

opening therein, a petticoat depending from said holder and having an opening therein, and a member bent upon itself to provide spaced substantially parallel arms designed to offer minimum resistance to the wind, said arms lodged in the openings of the holder and petticoat, respectively, and one of said arms fastening the petticoat to the holder.

14. In combination, a holder having an opening therein, a petticoat having a hole aligned with said opening of the holder, and a stop arm passing through said hole of the petticoat and lodged in said opening of the holder and securing the petticoat to the holder.

15. In combination, a cap having an opening therein, a petticoat having a hole aligned with said opening of the holder, and a stop

arm passing through said hole of the petticoat to the cap, said arm having a notch therein, a device passing through said cap and engaging said notch for locking said arm in position, and having a portion constituting a journal for a signal element.

16. A track obstacle, comprising a gravity track stop, a shaft connected thereto, a slide adapted to support said shaft, and a rotatable mount for said slide having its axis of rotation disposed substantially transversely to that of the shaft.

In testimony whereof I affix my signature in presence of two witnesses.

HERBERT R. NEVENS.
